(57) **CLAIM**

The ornamental design for the combined ceiling fan housing and light fixture, as shown and described.

DESCRIPTION

FIG. 1 is a bottom view of the combined ceiling fan housing and light fixture in accordance with my design;

FIG. 2 is a front elevation view of the combined ceiling fan housing and light fixture in accordance with my design;

FIG. 3 is a top view of the combined ceiling fan housing and light fixture in accordance with my design;

FIG. 4 is a side elevation view of the combined ceiling fan housing and light fixture in accordance with my design;

FIG. 5 is an enlarged partial front elevation view of the combined ceiling fan housing and light fixture in accordance with my design; and,

FIG. 6 is an enlarged partial top plan view of the combined ceiling fan housing and light fixture in accordance with my design.

The rear elevational view is substantially identical to the front except for the position of the blades.

The left and right side elevational views are substantially identical.

The broken line showing of environmental structure in FIGS. 1-6 is for illustrative purposes only and forms no part of the claimed design. The broken line showing of the fan blades in FIGS. 5-6 has been shown broken away for ease of illustration.
